BALL GAME APPARATUS

Robert J. Stutzenburg, Philadelphia, Pa.

Application August 29, 1933, Serial No. 687,254

16 Claims. (Cl. 273—95)

My invention relates to ball game apparatus, in the use of which balls may be thrown to a target forming part thereof, and a record made in simulation of the score which is kept for base-
5 ball and similar games.

The apparatus of my invention is particularly adaptable for use at carnivals, amusement parks, and similar places.

The principal object of my invention is to provide amusement apparatus, in the use of which balls may be thrown or projected to a suitable target forming part thereof, the device having means for indicating the place where each ball is thrown, to the end that the desired 10 tally may be kept.

A further object of my invention is to provide, in such apparatus, means for indicating mis-
thrown balls.

A further object of my invention is to provide, 20 in such apparatus, means for introducing variety into the use thereof, comprising an auxiliary target by means of which plays in the nature of bunted balls may be simulated.

A further object of my invention is to provide, 25 improved means for automatically returning the balls to the playing station after the indication of the play has been made.

A further object of my invention is to provide, 30 in such apparatus, means for indicating and controlling the time period of the play, whereby the apparatus will require a minimum of attention on the part of the attendant.

A further object of my invention is to provide, 35 an improved tallying device whereby the results of the various throws may be tallied in the form of a baseball score, simulating the various plays of that game.

With the foregoing objects in view, my invention contemplates the provision of a suitable 40 framework, having a ball receiving target at one end thereof and a playing station at the other end, means being provided in connection with the target for indicating the particular pocket into which each ball is thrown.

My invention further contemplates the provision of a suitable trough for returning the balls to the playing station after they have been thrown.

My invention further contemplates the provision of a substantially horizontal apron extending from the playing station to the target, having a plurality of apertures therein into which misthrown balls may pass to the trough for re-
55 turning the same to the playing station, and

means associated therewith for indicating the passage of the balls through said apertures.

My invention further contemplates the provision in the apron of an auxiliary target, relatively close to the playing station, comprising a series of apertures in the apron, and means associated therewith for indicating the passage of balls therethrough whereby the simulation of a bunted ball play may be obtained.

My invention further contemplates the provision, in connection with the playing station, of means for registering the various plays on a tallying device, and for keeping an accurate score of the game in simulation of the score kept in the well known game of baseball.

My invention further contemplates the provision, in connection with the playing station, of clock controlled means for automatically terminating the play, after a predetermined period, by stopping the delivery of balls, whereby the attendant may set the clocking mechanism so that, after a certain time period has elapsed, delivery of the balls to the player will be stopped.

My invention further contemplates the provision, in connection with the clock controlled means, of an audible signal adapted to notify the attendant of the termination of the time period.

The nature and characteristic features of my invention will be more readily understood from 30 the following description, taken in connection with the accompanying drawings forming part hereof, in which:

Fig. 1 is a side elevation of ball game apparatus embodying the main features of my present invention, the netting, which is commonly employed on the framework of apparatus of this general character, for preventing wildly thrown balls from passing outside of said framework, being removed;

Fig. 2 is a top or plan view of the apparatus shown in Fig. 1;

Fig. 3 is a horizontal section taken immediately below the apron, and illustrating the arrangement of the receivers and troughs for returning 45 the played balls to the playing station, the tallying device being shown in plan;

Fig. 4 is a transverse vertical section, taken at the rear of the apparatus, illustrating the target and play indicator in front elevation, the section 50 being taken approximately on the line 4—4 of Fig. 1;

Fig. 5 is a vertical central section of the rear portion of the apparatus;

Fig. 6 is an enlarged fragmentary elevational 55

view of a portion of the target, the view being taken in the direction of the arrow 6 shown in Fig. 5;

Fig. 7 is an enlarged fragmentary sectional view of a portion of the target, illustrating the construction and arrangement of the target pockets, with the circuit closing devices employed in connection therewith to cause the proper indicator lamp to remain lighted for a certain time interval, according to which of the pockets the ball is thrown into;

Fig. 8 is a front elevation of the tallying device, the time period controlling device also being shown in connection therewith;

Fig. 9 is a vertical sectional view illustrating the internal arrangement of the tallying device, the section being taken approximately on the line 9—9 of Fig. 8;

Fig. 10 is a horizontal section of the tallying and time period controlling devices, the section being taken approximately on the line 10—10 of Fig. 9;

Fig. 11 is a fragmentary detail of the arrangement of the scoring wheels of the tallying device;

Fig. 12 is a fragmentary detail view, enlarged, of a portion of the time period controlling device, the view being taken from the rear;

Fig. 13 is a side elevation showing the arrangement of switches forming part of the time period controlling device;

Fig. 14 is a detail view, partly in section, illustrating a portion of the means for controlling the delivery of the balls at the playing station;

Fig. 15 is a detail view, in plan, illustrating another portion of the means for controlling the delivery of the balls at the playing station; and

Fig. 16 is a diagrammatic view illustrating the wiring for controlling and actuating the various parts.

It will of course be understood that the description and drawings herein contained are illustrative merely, and that various changes and modifications may be made in the structure disclosed without departing from the spirit of my invention.

In the drawings, 20 is the framework which serves to support certain portions of the apparatus, as will later appear. The framework 20 may also be used for supporting a suitable network (not shown) which surrounds the apparatus at the sides and top, to prevent wildly thrown balls from passing beyond the bounds of the apparatus.

At the rear of the framework 20 a target 21 is mounted. The target 21 is preferably made of textile material such as canvas, the parts of which are suitably cut, shaped, and sewn together to provide a plurality of pockets 22. The floor member 23 of each of the pockets 22 is provided at its rear with an aperture 24, through which the ball which is thrown into the pocket may pass. The roof member 25 of each of the pockets 22 is inclined with respect to the floor member 23, and extends downwardly at the rear, where it is joined to said floor member at the rear of the aperture 24 therein.

The entire target structure 21 is inclined to the vertical, so that the roof member 25 of each pocket 22 has a pronounced inclination, which serves to direct the balls downwardly and to the rear whenever the same impact against said roof member 25 with any real force.

The target structure 21 being made of canvas or the like, and the parts being shaped as aforesaid, the flight of the ball will be arrested before

the ball passes through the aperture 24 to the means for indicating the particular pocket into which the same is thrown.

Secured to the floor member 23 of each pocket 22 is a trough 26, also preferably made of canvas, which catches the balls after they pass through the aperture 24 in said floor member 23, and directs the same to another trough 27, which is arranged at a slighter degree of inclination. The troughs 27 are preferably made of wood or other stiff material, and each of said troughs has mounted therein a pivoted counterbalanced tongue 28, which is adapted to be depressed by the passage of a ball through said trough 27.

A wire 29 extends transversely across the trough 27, so that when the tongue 28 is depressed, as aforesaid, by a ball rolling over the same, a contact will be made between the tongue 28 and the wire 29, for a purpose to be hereinafter explained.

Arranged below the series of troughs 27 which are provided, as aforesaid, one for each pocket 22, is a receiver box 30 (see Figs. 1 and 3), the bottom of which is inclined to direct the balls which fall therein to an outlet opening 31. An inclined trough 32 extends from a point below the outlet opening 31 in the receiver box 30 to the front end of the apparatus, where the playing station is located.

The target 21 is supported from the framework by means of canvas wings 31, which are made flaring with respect to the target proper, so as to deflect any balls which may impact against the same, and to afford a certain flexibility to the entire target structure, whereby the force of the balls will be more readily absorbed.

Extending from the target 21 to the playing station is a substantially horizontal canvas apron 33, which is divided into sections. Each of the sections has a depressed central portion which serves to guide the balls which fall thereon to openings 34, beneath which are located troughs 35, containing contacting devices similar in character to those shown in connection with the troughs 27 in the target pockets 22.

The sections of the apron 33 immediately in front of the target 21 are smaller than the other sections of said apron, so that the balls landing thereon will arrive more quickly at the points where the contact making devices are located. The openings 34 in the apron 33 immediately in front of the target 21 are disposed over branch extensions 36 of the return trough 32, whereas the openings 34 in the other sections of the apron may be disposed centrally, immediately over said return trough 32.

In one of the sections of the apron 33 adjacent the playing station, there is provided an auxiliary target comprising a plurality of openings 38 in said apron, so that the player may attempt to roll the balls into one of said openings 38 in a manner simulating the bunting of balls in a real game of baseball. Each of said openings 38 is provided with a trough 35 and a contact making device similar to those provided in connection with the pockets of the target 21, and with the other openings in the apron 33, so that when a ball passes through one of said openings 38 the same will be indicated in a manner to be presently explained. A branch 39 of the return trough 32 extends to a point beneath said openings 38, having an enlarged portion 40 at its terminus to catch the balls and return them to the main trough 32, and thence to the playing station.

Immediately below the target 21 there is provided an indicator 41, including a series of en-

cased lamps 42, one for each type of play to be indicated, and having suitable legends associated therewith, so that when a particular lamp is lighted the play may be manually recorded on the 5 tallying device, as will be hereinafter described.

The playing station comprises a barrier 43 extending across in front of the apparatus, having a table top 44, and a closed skirt 45 extending therefrom to the ground line. If desired, the 10 table top 44 may be used for the mounting thereon of a mechanical ball projecting device (not shown), or this may be dispensed with and the balls thrown by hand. The trough 32 for returning the balls to the playing station extends 15 through the front skirt portion 45 of the barrier a sufficient distance to expose one or two of the balls and render them accessible to the players.

At the right hand end of the barrier 43 of the playing station there is mounted a suitable cabinet 46 in which the tallying device and the clocking mechanism are located.

The tallying device is shown in Figs. 8, 9, 10 and 11 of the drawings. The cabinet 46 in which the same is mounted has a vertical indicating 25 panel 47, and a horizontal control panel 48. The means for indicating the total number of "runs" comprises two sets of numbered wheels 49, each set being mounted on a vertical shaft 50. The vertical panel 47 of the cabinet has a series of 30 window openings 51, through which one number on each wheel may be viewed when the wheel is turned to the proper indicating position.

Each of the numbered wheels 49 is provided with a pulley 52, fixedly secured thereto and operated by a belt 53. Each belt 53 extends to a grooved pulley 54 at the top of a vertical shaft 55. Each of the vertical shafts 55 has a grooved pulley 56 at the bottom thereof, over which a belt 57 passes (see Fig. 9).

40 Each belt 57 extends to a grooved pulley 58 mounted on the lower end of a shaft 59, which extends through the horizontal panel 48 and has a hand knob 60 at the upper end thereof, arranged above the top of the horizontal panel 48 of the cabinet, the arrangement being such that when any of the individual knobs 60 is operated, the corresponding number wheel 49 will be brought to the proper indicating position.

45 The same arrangement is provided for tallying the number of "outs", the number of "balls", and the number of "strikes". The numbered wheels 61 for such indications are mounted on a vertical shaft 62, and are operated by the hand knobs 63, disposed at the front end of the horizontal 55 panel 48, an arrangement of pulleys, belts and shafts being provided similar to those which are provided in connection with the wheels 49.

50 For indicating the positions of the runners on the several bases, there are provided four lamps 66, which are lighted and extinguished by means of manually operated switches 67. The lamps 66 may be mounted in the rear of the vertical panel 47 which is provided with suitable openings through which said lamps may be seen.

65 The clocking mechanism for controlling the time period is shown in Figs. 8, 9, and 12 of the drawings, the same comprising an electrically driven clock 68 of any preferred type, the dial 69 of which is visible through a suitable opening in the vertical panel 47 of the cabinet 46. Such clocks are usually provided with a setting spindle 70 extending through the rear wall of the clock casing, and upon this spindle 70 there is mounted a toothed wheel 71.

75 Another toothed wheel 72, normally out of en-

gagement with the toothed wheel 71, is mounted upon a longitudinally shiftable horizontal shaft 73. The toothed wheel 72 is normally held out of engagement with the toothed wheel 71 by means of a spring 74.

The other end of the horizontal shaft 73 is positioned adjacent an opening 75 in the side panel of the cabinet 46. This end of the horizontal shaft 73 is suitably shaped so as to be engaged by a key 76 inserted through the aperture 75, the key 76 being of such length that after it engages the end of the horizontal shaft 73, said shaft may be pressed inwardly to cause the toothed wheel 72 on the inner end thereof to engage the resetting wheel 71 of the clock.

10 The clock is preferably provided with but a single hand 77, which is adapted when it approaches the zero position to engage a contact arm 78 to close an alarm circuit, and when it reaches the zero position to engage another contact arm 79 to open a circuit for controlling the delivery of the balls from the return trough 32.

15 The means for controlling the delivery of the balls, when it is desired to stop the same after a predetermined time period has elapsed, is shown in Figs. 14 and 15 of the drawings. As there shown, there is provided above the return trough 32, and preferably behind the skirt portion 45 of the barrier 43 at the playing station, a solenoid coil 80.

20 The core 81 of the solenoid coil 80 carries at its lower end a stop member 82, which is adapted, when the solenoid core 81 is free, to rest upon the top edges of a shallow portion of the return trough 32, and when so positioned, to prevent the passage of the balls 83 through said trough. The upper end of the solenoid core 81 is pointed as at 84, and below this pointed portion 84 there is provided an annular recess 85, which is adapted, when the solenoid core 81 is raised to its uppermost position, to be engaged by a lever 86, which is pivoted as at 87. The lever 86 is normally impelled to its engaging position by means of a spring 88.

25 The lever 86 also carries an armature 89, which is positioned adjacent the end of an electromagnet 90, the arrangement being such that when the magnet 90 is energized the lever 86 will be pulled to a position to disengage the end of said lever from the recess 85 at the top end of 30 the solenoid core 81.

35 The pointed end 84 of the solenoid core 81 is also adapted, when it reaches its uppermost position, to engage a spring arm 91, which carries a contact member 92. When the solenoid core 81 is in its lowermost position, the contact member 92 engages another contact member 93, which is connected to the solenoid coil 80 by wire 94. The arrangement is such that when current is supplied to the solenoid coil, if the core 81 thereof is in its lowermost position to effect the stopping of the balls, the coil 80, being energized, will pull the core 81 upwardly until the recess 85 thereof is engaged by the end of the lever 86, which will then hold it in the raised position. Simultaneously the end of the core 81 will engage the spring 91, breaking the contact between members 92 and 93, which will prevent the further supply of current to the coil 80; but, as before stated, when this occurs, the solenoid core 40 45 55 60 65 70 75 81 will be held in its uppermost position by the engagement of the lever 86 in the recess 85 thereof. When, however, the magnet 90, is energized, the armature 89 carried by the lever 86 will be attracted to cause the end of said lever to be-

come disengaged from the recess 85, and thereby permit the core 81 to drop.

In Fig. 16 of the drawings there is shown an arrangement of the circuits employed, and the parts controlling the same and controlled thereby. As there shown, 100 and 101 are the main power lines, controlled by a master switch 102, which is preferably mounted, as shown in Fig. 12 of the drawings, inside the housing of the tallying cabinet 46, and adapted to be manually actuated by the key 76 which is also used for resetting the clock mechanism. The side panel of the cabinet 46 is provided with a suitable aperture 103 for the insertion of the key 76 when it is desired to turn the switch off or on.

A line 104, with suitable branches, extends from the power line 100 to the stationary contact members 29 in the troughs 27 provided in connection with the pockets 22 in the target 21. A series of lines 105 extends from the respective movable members 28 of said troughs 27 to the respective lamps 42 provided in the indicator 41 arranged below the target 21. Return lines 106, with suitable branches, extend from said lamps 42 to the power line 101.

A line 107, with suitable branches, extends from the power line 100 to the movable members 108 of the contact devices which are provided in the troughs 35 below the main return openings 34 in the apron 33. The stationary members 109 of the contact devices in said troughs 35 are connected by lines 110 to the lines 105 which extend to the respective lamps 42 in the indicator 41.

Likewise a line 111, with suitable branches, extends from the main power line 100 to the movable members 112 of the contact making devices provided in the troughs 35 below the openings 38 for indicating the "bunted ball" plays. The stationary members 113 of said contact making devices are connected by lines 114 to the respective lamps 42 for indicating such plays.

A line 115, with suitable branches, extends from the main power line 100 to the manually operated switches 67 which control the lamps 66 for indicating the base positions resulting from the individual plays. Lines 116 extend from the switches 67 to the respective lamps 66 controlled thereby, and a common return line 117, with suitable branches, extends from said lamps 66 to the main power line 101.

A line 118 extends from the main power line 100 to the clock 68, the current returning from the clock by line 119, which extends to the movable arm 79 of the switch which is adapted to be actuated to the open position by the hand 77 of the clock 68 when said hand returns to the zero position. The stationary member 120 of the switch is connected by line 121 to power line 101.

A shunt line 122 extends from line 118, which as before stated is connected with the main power line 100, to the spring arm 91, the current passing through the same to contact member 92. As hereinbefore stated, the member 93, with which the member 92 is adapted to contact, is connected by line 94 to one end of the solenoid coil 80. The other end of the solenoid coil 80 is connected by line 123 to the movable arm 79 of the switch which is controlled by the clock hand 77.

By this arrangement, whenever the switch arm 79 is opened by the return of the clock hand 77 to the zero position, not only will the clock 68 be stopped by the opening of the circuit in which it is included, but the coil of the solenoid will

also be de-energized to permit the stop member 82 of the ball controlling device to fall to the position to stop the delivery of balls to the trough 32.

Another shunt line 124 extends from the line 122 to an alarm bell 125, which is also connected by line 126 to a contact member 127, which is so positioned as to be engaged by the switch member 78 when the same is actuated by the clock hand 77 as the same approaches the zero position.

Another shunt line 128 extends from line 124 to one end of the electromagnet coil 90, the other end of which is connected by line 129 to line 126, so that the electromagnet coil 90 will be energized upon the closing of the circuit in which the alarm bell 125 is included.

The operation of the device may now be explained. The players having assembled at the playing station, and having divided themselves into two equal groups each representing a baseball team, the attendant puts the apparatus into operation by pushing the key 76 through the aperture 103, causing the same to engage the end of the shaft of the main switch 102 which controls the supply of current through the main power lines.

The operator then pushes the key 76 through the aperture 75, causing the same to engage the end of the shaft 73. The key 76 is pushed inwardly to shift the shaft 73 longitudinally against the tension of the spring 74, until the toothed wheel 72 engages the toothed wheel 71 of the clock 68. The key 76 is then turned to cause the clock hand 77 to be turned contra-clockwise, until the same is brought to a position corresponding to the time period for which payment is made by the players.

When the clock hand 77 is thus moved away from the zero position, the contact arm 79 engages the stationary contact member 120, whereby current is supplied to the clock 68 from power line 100, through line 118, passing through the clock 68, thence passing by line 119 through the switch arm 79 and returning to power line 101 by line 121.

Simultaneously the current will pass by shunt line 122 to spring 91, through contact members 92 and 93, thence through wire 94 to the solenoid coil 80, passing through and energizing the same, and thence passing to the switch arm 79 by line 123. When the solenoid coil 80 is thus energized, the stop member 82 will be lifted, permitting the balls 83 to roll through the trough 32 to the delivery point.

When the solenoid coil 80 is thus energized, its core 81 will be raised to the uppermost position, until the end 84 thereof engages the spring arm 91, breaking the contact between the members 92 and 93, and thus opening the circuit through the solenoid coil 80 while the play progresses. However, when this occurs, the end of the lever 86 will engage the recess 85 in the projecting upper end of the core 81, by reason of the tension of the spring 88, and the stop member 82 will thus be held in the elevated position, notwithstanding the de-energization of the coil 80.

The players then cause the balls to be projected toward the target 21, either by means of a mechanical ball throwing device (not shown) or by hand.

Assuming that the ball reached the target structure 21, the same will pass into one of the pockets 22 thereof. If the ball be projected with any great degree of force, the impact will be ex-

panded against the roof member 25 of the pocket, but in any event, the ball will pass through the aperture 24 at the rear of the pocket, thence falling into the trough 26, by means of which it is 5 guided into the trough 27 in which the contact device is mounted.

When the ball passes into the trough 27 in which the contact device is mounted, the contact arm 28 will be depressed by the weight of 10 the ball, and will establish a contact with the wire 29 which is located in the bottom of the trough 27, thereby establishing a circuit to cause the proper lamp 42 at the indicator 41 to be lighted.

15 The trough 27 is arranged at a slight angle of inclination, so that the passage of the ball therethrough will be delayed to cause the lamp 42 to remain lighted a sufficient length of time to insure a full opportunity to observe the indication. 20 After the ball passes through the trough 27, the same falls into the receiver box 30 at the bottom and to the rear of the target 21, and thence passes to the return trough 32, which has a sufficient inclination to cause the ball to return to the playing 25 station.

If the ball should fail to reach one of the pockets 22 of the target, it will fall upon the apron 33 and pass through one of the apertures 34 in said apron to the trough 35 which is located below the same. As each of these troughs 35 has contact members 108 and 109, similar to the contact members in the trough 27, a circuit will be established and the corresponding lamp 42 lighted at the indicator 41.

30 Whenever the ball passes through one of the apertures 34 in the apron 33, the same, after passing through the trough 35 in which the indicator switch is located, will fall into the return trough 32 or into one of the branches there- 35 of.

40 Likewise, if the auxiliary target be used to simulate bunted ball plays, whenever the ball passes into one or the other of the apertures 38 in said target, the same will pass into one of the troughs 35 positioned below the same, and here again a contact will be established by the contact members 112 and 113, and a circuit closed to cause the proper lamp 42 at the indicator 41 to be lighted.

50 Whenever the ball passes through one of the openings 38 of the auxiliary target, the same will fall into the proper trough 35 containing the contact device, will then pass into the receiver box 40, and thence by branch trough 39 to trough 32.

55 If the lamp 42 which is lighted on the indicator 41 indicates an "out", a "ball", or a "strike", the same is registered by the manipulation of one of the hand knobs 63, said knob being turned to rotate the numbered wheel 61 on the shaft 62.

60 If the lamp 42 on the indicator 41 indicates a base hit, whether single, double, or triple, one or more of the manually operated switches 61 is actuated to light or extinguish, as may be required, the proper lamp or lamps 66 at the upper 65 right hand portion of the cabinet 46, for the purpose of recording the base scoring.

70 Whenever a "home run" is indicated by the proper lamp 42 on the indicator 41, or whenever a run results by the addition of base plays, the same is scored on the proper innings wheel 49 by the manipulation of the proper hand knob 60, the motion of said hand knob being transmitted by means of its vertical shaft 59 and pulley 58, through the belt 57 to one of the vertical shafts 55 at the rear of the cabinet 46, thence

being transmitted by the pulley 54 at the top of said shaft 55, by the belt 53, to the proper numbered wheel 49.

The scoring is kept as in the real game of baseball, the tallying device being operated in accordance with the indications of the lamps 42 which are brought about by the projected balls, whether the same be thrown into one of the pockets 22 of the target 21, or fall upon the apron 33, or are rolled into one of the apertures 38 of the auxiliary target. 10

As the playing continues, the time clock 68 will be operating, and when the hand 77 of the clock reaches a point in its movement just prior to the zero position, the same will engage the 15 contact arm 78, causing it to bear against the stationary contact member 127, thereby completing the circuit in which the alarm bell 125 is arranged. This will call the attention of the operator to the fact that the period of play which has 20 been paid for by the players is about to terminate, so that he may arrange with the players for a continuance of the play if so desired, in which event the clock 68 will be reset for the proper period. 25

When the circuit in which the alarm bell 125 is included is closed, simultaneously the current will pass through shunt line 129 to the electromagnet 99, energizing the same, and returning by line 129. When the electromagnet 99 is thus 30 energized, the armature 99 carried by the lever 86 will be attracted, causing the end of the lever 86 to be freed of engagement with the recess 85 in the projecting upper end of the solenoid core 81, releasing the same and permitting the 35 stop member 82 to fall and prevent further delivery of balls through the trough 32.

If the players do not wish to continue, the attendant, by operation of the main switch 102, by means of the key 76, may shut off the current for 40 the entire apparatus.

When the hand 77 of the clock 68 reaches the zero position, the same will encounter the switch arm 79, raising the same from the stationary contact member 129 and opening the circuits controlled by said switch 79. This will not only cause the clock 68 to cease operating, but will also cause the solenoid coil 89 to be de-energized. 45

It will be noted that the arrangement is such that a single attendant may easily look after the 50 operation of a number of the devices, by reason of the alarm provided, and the automatic discontinuance of the supply of balls.

I claim:

1. In a ball game apparatus, a target at one end, 55 a playing station structure at the other end, an apron extending from the target to the playing station structure, an indicator, a trough for returning the balls from the target to the playing station, said trough extending beneath the apron, 60 an auxiliary target device comprising a series of apertures in the apron near the playing station through which balls may pass to the return trough, and contact making devices positioned to be actuated by balls passing through said 65 apertures, said contact making devices being electrically connected with the indicator.

2. In a ball game apparatus, a target at one end, a playing station structure at the other end, an apron extending from the target to the playing station structure, an indicator, the target comprising a series of pockets adapted to receive 70 balls projected from the playing station, contact making devices for each of said pockets, said contact making devices being electrically connected 75

with the indicator, a trough for returning the balls from the target to the playing station, said trough extending beneath the apron, an auxiliary target device comprising a series of apertures in the 5 apron near the playing station through which balls may pass to the return trough, and contact making devices positioned to be actuated by balls passing through said apertures, said contact making devices being electrically connected with the 10 indicator.

3. In a ball game apparatus, a target at one end, a playing station structure at the other end, an apron extending from the target to the playing station structure, an indicator, a trough for returning the balls from the target to the playing 15 station, said trough extending beneath the apron, the apron having a series of apertures through which balls may pass to the return trough, and contact making devices positioned to be actuated by balls passing through said apertures, said contact making devices being electrically connected with the 20 indicator.

4. In a ball game apparatus, a target at one end, a playing station structure at the other end, 25 an apron extending from the target to the playing station structure, an indicator, the target comprising a series of pockets adapted to receive balls projected from the playing station, contact making devices for each of said pockets, said contact making devices being electrically connected with the 30 indicator, a trough for returning the balls from the target to the playing station, said trough extending beneath the apron, the apron having a series of apertures through which balls may 35 pass to the return trough, and contact making devices positioned to be actuated by balls passing through said apertures, said contact making devices being electrically connected with the indicator.

5. In a ball game apparatus, a target at one end, a playing station structure at the other end, an apron extending from the target to the playing station structure, an indicator, the target comprising a series of pockets adapted to receive 45 balls projected from the playing station, contact making devices for each of said pockets, said contact making devices being electrically connected with the indicator, a trough for returning the balls from the target to the playing station, said 50 trough extending beneath the apron, the apron having a series of apertures through which balls may pass to the return trough, contact making devices positioned to be actuated by balls passing through said apertures, said contact making devices being 55 electrically connected with the indicator, an auxiliary target device comprising a series of apertures in the apron near the playing station through which balls may pass to the return trough, and contact making devices positioned to be actuated by balls passing through said apertures, said contact making devices being electrically connected with the indicator.

6. In a ball game apparatus, a target at one end, a playing station structure at the other end, an apron extending from the target to the playing station structure, an indicator, the target comprising a series of pockets adapted to receive 65 balls projected from the playing station, contact making devices for each of said pockets, said contact making devices being electrically connected with the indicator, a trough for returning the balls from the target to the playing station, said trough extending beneath the apron, the apron having a series of apertures through which balls may 70 pass to the return trough, contact making devices being electrically connected with the indicator.

devices positioned to be actuated by balls passing through said apertures, said contact making devices being electrically connected with the indicator, an auxiliary target device comprising a series of apertures in the apron near the playing 5 station through which balls may pass to the return trough, contact making devices positioned to be actuated by balls passing through said apertures, said contact making devices being electrically connected with the indicator, a clocking device, and electrically actuated means controlled by said clocking device for preventing passage of the balls through the return trough at the end of a predetermined time period.

7. In a ball game apparatus, a target at one end, a playing station structure at the other end, an apron extending from the target to the playing station structure, an indicator, the target comprising a series of pockets adapted to receive 15 balls projected from the playing station, contact making devices for each of said pockets, said contact making devices being electrically connected with the indicator, a trough for returning the balls from the target to the playing station, said trough extending beneath the apron, the 20 apron having a series of apertures through which balls may pass to the return trough, contact making devices positioned to be actuated by balls passing through said apertures, said contact making devices being electrically connected with the indicator, an auxiliary target device comprising a series of apertures in the apron near the playing 25 station through which balls may pass to the return trough, contact making devices positioned to be actuated by balls passing through said apertures, said contact making devices being electrically connected with the indicator, a clocking device, and electrically actuated means controlled by said clocking device for preventing passage of the balls through the return trough at the end of a 30 predetermined time period.

8. In a ball game apparatus, a target at one end, a playing station structure at the other end, a trough for returning the balls from the target to the playing station, a clocking device, electrically actuated means controlled by said clocking device for preventing passage of the balls through the return trough at the end of a 45 predetermined time period, and an electrical alarm device controlled by the clocking device and adapted to be set in actuation thereby.

9. In a ball game apparatus, a target at one end, a playing station structure at the other end, a trough for returning the balls from the target to the playing station, a clocking device, electrically actuated means controlled by said clocking device for preventing passage of the balls through the return trough at the end of a 50 predetermined time period, and an electrical alarm device controlled by the clocking device and set in actuation thereby prior to the end of said predetermined time period.

9. In a ball game apparatus, a target made 55 of textile material and having a plurality of pockets, each of said pockets including a floor member and an impact receiving roof member inclined with respect to said floor member, said members being spaced from the roof and floor members of adjoining pockets, the rear portion 60 of said roof member extending downwardly toward said floor member, an aperture formed in said floor member through which balls are adapted to pass, and contact making devices for actuation by a ball discharged through said aperture.

10. In a ball game apparatus, a target made 65 of textile material and comprising a plurality of pockets, each of said pockets having a floor member and a roof member inclined with respect to 70 said floor member, said members being spaced from the roof and floor members of adjoining pockets, the rear portion of said roof member extending downwardly toward said floor member, an aperture formed in said floor member through 75

which balls are adapted to pass, and contact making devices arranged adjacent said aperture for actuation by a ball discharged through said aperture.

actuation by a ball discharged through said aperture, and flaring wings of textile material supporting said target.

5 11. In a ball game apparatus, a target made of textile material and comprising a plurality of pockets, each of said pockets having a floor member and an impact receiving roof member inclined with respect to said floor member, said 5 members being spaced from the roof and floor members of adjoining pockets, the rear portion 10 of said roof member being extended downwardly to said floor member, an aperture formed in said floor member through which balls are adapted 15 to pass, a trough of textile material arranged below said aperture, a second trough into which said first trough discharges, and contact making devices arranged in said second trough for actuation by a ball discharged into said second trough, 20 the said second trough being arranged at a slight angle of inclination thereby to delay the passage of a ball therethrough and provide a persisting contact.

12. In ball game apparatus, an inclined target 25 made of textile material and having the face thereof divided horizontally and vertically to provide a plurality of pockets, each of said pockets including a floor member and an impact receiving roof member inclined with respect to said 30 floor member, said members being spaced from the roof and floor members of adjoining pockets, the rear portion of said roof member extending downwardly toward said floor member, and an aperture formed in said floor member through 35 which balls projected into said pocket are adapted to be discharged.

13. In a ball game apparatus, an inclined target made of textile material and having the face thereof divided horizontally and vertically to provide 40 a plurality of pockets, each of said pockets including a floor member and an impact receiving roof member inclined with respect to said floor member, said members being spaced from the roof and floor members of adjoining pockets, the 45 rear portion of said roof member extending downwardly toward said floor member, an aperture formed in said floor member through which balls are adapted to pass, contact making devices for

14. In a ball game apparatus, an inclined target made of textile material and having the face thereof divided horizontally and vertically to provide a plurality of pockets, each of said pockets including a floor member and an impact receiving roof member inclined with respect to said floor member, said members being spaced from the roof 10 and floor members of adjoining pockets, the rear portion of said roof member being extended down to said floor member, the said floor and roof members being sewn together, an aperture formed in said floor member through which balls are 15 adapted to pass, contact making devices for actuation by a ball discharged through said aperture, and flaring wings of textile material providing a support for said target and said contact making devices. 20

15. In a ball game apparatus, a plurality of troughs arranged at various places to receive projected balls, each of said troughs having an elongated contact device extending longitudinally therein and actuated by a ball passing through 25 said trough to operate said contact device during a substantial period of time, and an indicator to which said contact devices are electrically connected thereby to show by the passage of the ball through one of said troughs the place to which 30 said ball was thrown.

16. In a ball game apparatus, a target having a face made up of a plurality of individual pockets each having a discharge outlet, a trough arranged at a slight angle of inclination at the rear end of 35 each of said pockets and into which balls passing through said outlet are directed, the slight angle of inclination effecting a delayed passage of balls through the trough, an elongated contact device extending longitudinally of the trough 40 operated by the ball during its passage through the trough, the contact device being positioned to be actuated by a ball during a substantial period of time in the travel of the ball through the trough, and an indicator to which said contact 45 device is electrically connected.

ROBERT J. STUTZENBURG.
